UNITED STATES PATENT OFFICE.

JOEL BARKER, OF IRVINE, KENTUCKY.

SELF-CLEANING SPARK-PLUG.

1,297,058.

Specification of Letters Patent. Patented Mar. 11, 1919.

Application filed April 30, 1918. Serial No. 231,654.

To all whom it may concern:

Be it known that I, JOEL BARKER, a citizen of the United States of America, residing at Irvine, in the county of Estill and State of Kentucky, have invented new and useful Improvements in Self-Cleaning Spark-Plugs, of which the following is a specification.

The present invention comprehends generally improvements in that class of inventions known as internal combustion engines and more particularly relates to a self cleaning spark plug.

It is the primary aim and object of this invention to provide a device of the above mentioned character designed so as to actuate simultaneously with the operation of the piston in the adjacent cylinder of an engine to prevent the accumulation of soot or carbon on the casing and the stem of the spark plug and thus avoid a premature firing or back-firing of gases in the cylinder of the engine.

As an equally important object the present invention contemplates the provision of a spark plug wherein a cleaning element of a novel construction is mounted for reciprocatory movement in the casing of the spark plug and actuates in timed relation with the operation of the piston in the adjacent engine cylinder to assure of a complete exhausting of burnt gases from the casing of the spark plug and also of the accumulation of fresh gases near the sparking points of the spark plug so that the fresh gases may be readily and quickly fired at the proper time.

More particularly the present invention embraces the provision of a cleaning element in the form of a piston slidably mounted on the stem of a spark plug and designed to receive packing rings to assure of an air tight engagement between the element and the casing and between the element and the stem.

Among the other aims and objects of this invention may be recited the provision of a device of the character described with a view to compactness, and in which the number of parts are few, the construction simple and the cost of production low and the efficiency high.

Other improvements and novel details in the construction and arrangement of the various parts of the apparatus will be brought out more in detail in the description to fol-

low, which for a clear understanding of the invention should be considered in connection with the accompanying drawings forming a part hereof, and wherein is disclosed for the purpose of illustration a convenient and satisfactory embodiment of the invention. It is to be noted in this connection that minor changes may be made without departing from the principle of operation of the various parts.

The invention is clearly illustrated in the accompanying drawings, in which—

Figure 1 is a vertical section of the invention showing the cleaning element in a raised position.

Fig. 2 is a similar view showing the cleaning element in a lowered position.

Fig. 3 is a horizontal section taken on line 3—3 of Fig. 1, and

Fig. 4 is a horizontal section taken on line 4—4 of Fig. 1.

Similar characters of reference are employed in all of the above described views, to indicate corresponding parts.

Referring now, more particularly, to the accompanying drawings, there is provided a spark plug consisting of a cylindrical casing 1 the outer surface thereof near the lower end being tapered and threaded as at 2 for engagement with the top of an engine cylinder while the upper edge is inclined downwardly from the outer surface to the inner surface as at 3 for a purpose that will become apparent. An annular shoulder 4 is formed on the inner surface of the casing near the lower edge thereof for a purpose that will hereinafter become apparent and likewise the casing is provided medially its ends with small openings 5. Fitted within the upper end of the casing is an insulating element 6 formed preferably of porcelain and being designed to support a pole or wire 7, the lower end of which constitutes one of the sparking points. This insulated element consists of a body 9 which is reduced as at 10 to form an inclined shoulder 11 which seats against the upper inclined edge 3 of the casing while the lower reduced portion 10 of the body is arranged in close relation with the inner surface of the casing. The lower portion of the body 8 is again reduced to form a shoulder 12 so that the intermediate lower reduced portion will be arranged in spaced relation to the inner surface of the casing so that air may pass through the openings 5 and be exhaust-

ed through the openings 5 in a manner that may hereinafter become apparent. A stem 13 is integral with the intermediate lower end of the body and depends therefrom, 5 being also designed to support the lower portion of the wire 7. A binding post 14 is formed on the upper portion of the body while the upper edge of the body is inclined as at 15 from the post to the outer 10 edge of the body as indicated in the drawings. A head indicated in its entirety by the numeral 16 is now employed and is preferably in the form of a nut, the upper portion being of a frusto-conical form as at 17 15 and formed with an opening 18 which is arranged about the post 14 to permit the frusto-conical portion to seat against the inclined upper edge of the body. The inner surface of the lower portion of the head is 20 formed with threads 19 for engagement with a correspondingly formed outer surface of the casing. The outer surface of the head is of a hexagonal form as indicated by the numeral 20 so as to be readily engaged by a 25 wrench to assure of the adjusting of the head on the casing and consequent clamping of the insulating element in a proper position. A clamping nut 21 is adjustably mounted on the upper portion of the pole 30 or wire 7 to facilitate the clamping of a conducting wire (not shown) thereto. Another 35 sparking point 22 extends from the lower edge of the casing and terminates near the lower sparking point 7.

As intimated, improved means have been 40 provided for assuring of the cleaning of the spark plug so as to prevent accumulation of soot and gases on the casing and pole and also for exhausting any burnt gases 45 from the casing of the spark plug during the operation of the engine in which the spark plug is mounted. In reducing this feature of the invention to practice an improved cleaning element 23 is employed and 50 is preferably in the form of a piston which is provided with a center opening 24 for slidable engagement with the stem 13 while the outer periphery thereof is formed with an annular groove 25 in which is accommodated a packing ring 26 for assuring of an air tight engagement between the piston head and the casing to prevent air passing 55 by the piston head and entering the lower portion of the spark plug casing. The head is formed with a collar 27 which depends from the lower edge thereof about the opening 24 therein, while the outer surface of the collar is threaded as at 28. A relatively 60 small packing ring 29 is now arranged about the stem and is held in close relation with the lower edge of the collar by a tubular jam nut 30 which assures of the movement of the small ring 29 with the head. The upward movement of the piston shaped 65 cleaning element 23 is limited by the lower

reduced portion of the insulating element while the downward movement is limited by the annular shoulder 4.

In use, assuming that the device has been assembled in the manner described and as 70 illustrated in the drawings, upon the intake stroke of a piston of an engine (not shown) the suction in the cylinder serves to direct the piston shaped cleaning element 23 downwardly in the casing 1, the downward movement being limited by the shoulder 4. This action of the piston shaped cleaning element 75 serves to exhaust any burnt gases from within the spark plug casing and also prevents the accumulation of carbon or soot on the 80 inner surface of the casing and on the stem 13. On the compression stroke the pressure of the gases in the cylinder of the engine (not shown) acts against the piston shaped 85 cleaning element and forces the latter upwardly until it abuts the lower edge of the reduced portion 12 of the insulating element. Of course, air which has previously 90 been admitted in the upper portion of the casing in the holes or openings 5 is exhausted through these openings during the upward movement of the cleaning element. Inasmuch as fresh gases are allowed to 95 congregate about the sparking points an effective firing of these gases on the firing stroke or pressure of the gases acts to hold the piston shaped cleaning element in its upward position and, of course, on the exhaust or admission stroke the piston shaped 100 cleaning element 23 is held in a raised position. This operation of parts is repeated during 105 each continued operation of the engine. In some instances the accumulation of the carbon or soot on the casing and stem of the spark plug causes the back-firing or the premature firing of the gases within the cylinder of the engine (not shown). It is to be appreciated, however, that this is obviated by the improved cleaning element 110 which operates simultaneously with the operation of the engine.

It is believed in view of the foregoing description of the invention that a further detailed description of the operation of the invention is entirely unnecessary. Likewise 115 it is believed that the advantages of the invention will be readily apparent.

As many changes could be made in the above construction and many apparently widely different embodiments of this invention could be made without departing from the scope thereof it is intended that all matter contained in the above description or shown in the accompanying drawings shall be interpreted as illustrative and not in a 120 limited sense. It is also to be understood that the language used in the following claim is intended to cover all the generic and specific features of the invention herein-described and all statement of the scope of 125 130

the invention which as a matter of language might be said to fall therebetween.

Having thus fully described the invention what is claimed and desired to be secured by 5 Letters Patent is:

A spark plug of the character described comprising a cylindrical casing designed for attachment to the cylinder of an internal combustion engine and formed with air inlet and exhaust openings, an annular shoulder formed on the inner surface of the casing near the lower edge thereof, a pole supporting body formed of insulating material mounted on the upper edge of the casing, a 15 pole supporting stem integral with the insu-

lating body and depending therefrom, a piston shaped cleaning element slidably mounted on the stem and limited in its upward movement by the lower edge of the body and its downward movement by the shoulder, a 20 packing ring mounted on the outer surface of the piston shaped cleaning element, a collar depending from the element, a packing ring associated with the collar and bearing against the stem and a tubular jam nut 25 connected to the collar for supporting the last mentioned ring.

In testimony whereof I affix my signature.

JOEL BARKER.
